UNITED STATES PATENT OFFICE.

JOHN KIEWICZ, OF BOSTON, MASSACHUSETTS, ASSIGNOR TO THE REECE BUTTON HOLE MACHINE COMPANY, OF BOSTON, MASSACHUSETTS, A CORPORATION OF MAINE.

BUTTONHOLE-SEWING MACHINE.

1,248,134.

Specification of Letters Patent.

Patented Nov. 27, 1917.

Application filed January 17, 1917. Serial No. 142,816.

To all whom it may concern:

Be it known that I, JOHN KIEWICZ a citizen of the United States, residing at Boston, county of Suffolk, State of Massachusetts, have invented an Improvement in Buttonhole-Sewing Machines, of which the following description, in connection with the accompanying drawing, is a specification, like characters on the drawing representing like parts.

This invention relates to buttonhole sewing machines of that familiar type in which the work-holding means and stitch-forming mechanism are given their relative movements by means of a feed cam, and in which when the machine is started in operation the feed cam has first a comparatively rapid movement thereby producing a comparatively quick relative movement between the work-holding means and stitch-forming mechanism to carry the parts from button-hole-cutting to stitching position, and after the parts have reached stitching position, the stitching mechanism is set in operation and the feed cam is given a comparatively slow step-by-step movement to produce a relative feeding motion between the work-holding means and stitch-forming mechanism, this feeding movement continuing as the stitching is performed along first one side and then the other of the button-hole, and after the stitching operation is completed and the stitch-forming mechanism is brought to rest, the feed cam is given a comparatively rapid movement thereby to produce a quick relative movement between the work-holding means and stitch-forming mechanism to move the parts from stitching to buttonhole-cutting position.

In sewing machines of this type it is common to provide two separate driving mechanisms for the feed cam, one of which gives the cam a relatively-quick movement thereby to produce the rapid relative movement between the work-holding means and stitch-forming mechanism to carry these parts from buttonhole-cutting to stitching position, or from stitching to buttonhole-cutting-position, and the other of which driving mechanisms operates to give the feed cam a relative slow step-by-step movement during the stitching operation, thus producing the necessary feeding movement of the work. In sewing machines of this type,

means are provided for disconnecting the quick-feed driving mechanism when the parts have been brought from buttonhole-cutting to buttonhole-stitching position, and at the same time to connect the slow feed driving mechanism. In the operation of a sewing machine of this type, it is important that there should be no overlapping of operation between the quick-feed driving mechanism and stitch-forming mechanism, for if it should happen that when the parts are brought from buttonhole-cutting to stitching position, the stitch-forming mechanism should be set in operation before the quick-feed driving mechanism has been completely thrown out of operation, so that there is a slight overlapping of operations at this point, the needle of the stitching mechanism will be caused to penetrate the work before the comparatively rapid movement between the stitch-forming mechanism and work-holding means has ceased, and the result is apt to be a broken needle or broken thread.

One of the objects of my present invention is to provide a novel mechanism for controlling the operation of the quick-feed driving mechanism and the stitch-forming mechanism so that there shall be no overlapping of operations and which shall insure that the quick-feed movement will be arrested before the stitch-forming mechanism is set in operation so that the first penetrating thrust of the needle on any buttonhole will inevitably be the relatively-slow movement.

Other objects of my invention are to improve buttonhole sewing machines in various other particulars, all as will be more fully hereinafter set forth.

In order to give an understanding of my invention, I have illustrated in the drawings a selected embodiment thereof which will now be described, after which the novel features will be pointed out in the appended claims.

Figure 1 of the drawings is a side view of a sewing machine embodying my invention with the base frame broken away to better show the construction;

Fig. 2 is an underside view of the machine;

Fig. 3 is a plan view of the stitching clutch and its associated parts;

Fig. 4 is a section on the line 4—4, Fig. 2;
 Fig. 5 is a section of the line 5—5, Fig. 2;
 Fig. 6 is a detail view of one of the
 clutches employed;

5 Fig. 7 is a view showing the controlling
 cam;

Fig. 8 is a section on the line 8—8, Fig. 2.

The principal parts of the sewing machine herein illustrated are the same as those
 10 usually found in sewing machines of this type and particularly the same as those illustrated in my co-pending application Se. No. 100,124, filed May 26, 1916. Inasmuch as the present invention relates particularly to the means for controlling the
 15 operation of the quick-feed driving mechanism and the stitch forming mechanism, it will not be necessary to describe in detail all of the elements of the sewing machine. I
 20 will, however, refer briefly to the main elements of the sewing machine.

1 indicates a frame of the machine which carries upper-thread-handling mechanism in the form of a needle 2 and its reciprocating
 25 needle bar 3 and under-thread-handling mechanism indicated generally at 4, these upper and under-thread-handling mechanisms being such as illustrated in United States Patents No. 655,637, dated August 7,
 30 1900, and No. 1,030,589, dated June 25, 1912. Both the upper and under-thread-handling mechanisms are constructed for rotary movement during the stitching around a buttonhole, this rotary movement being secured by pinions 5 and 6 carried by the upper and under-thread-handling mechanisms, respectively, which mesh with segmental racks 7 and 8 carried by an oscillatory shaft 9, all as shown in the above-mentioned pat-
 40 ents.

The work-holding means by which the work is held during the stitching operation comprises a clamp plate 10 on which the work is supported and work clamps 11 that
 45 are adapted to be moved toward and from the clamp plate 10 to clamp the work in position or to release it. The work-holding means and stitch-forming mechanism are arranged for movement relative to each
 50 other, and in the construction herein illustrated, this is provided for by giving the clamp plate 10 and work clamps 11 a movement relative to the frame 1. This movement of the work clamp is secured from a
 55 slide 12 mounted in the bed of the frame 1 for reciprocating movement, said slide receiving such reciprocatory movement from a feed cam 13, all as usual in sewing machines of this type.

60 14 indicates a buttonhole cutter which is rendered operative at the proper point in the cycle of operations to cut the buttonhole.

In sewing machines of this type, the machine is brought to rest at the end of each

cycle of operations with the parts in buttonhole-cutting position, and when the machine is started the work is first clamped in the work-holding means and the buttonhole cutter 14 is then operated to cut the buttonhole, after which the feed cam 13 is given a relatively-quick movement thereby quickly moving the work-holding means from buttonhole-cutting to stitching position, at which time the stitch-forming mechanism is set in operation and the feed cam is operated with a relatively slow step-by-step movement to provide the necessary feeding movement to the work. When the buttonhole has been completely stitched, the stitch-forming mechanism is brought to rest and the quick-feed mechanism is again thrown into operation to quickly return the work-holding means to buttonhole-cutting position. The feed cam 13 is operated from a worm 140 carried by a shaft 15.

The quick-feed driving mechanism above referred to comprises a driving pulley 16 loosely mounted on the shaft and a clutch 17 by which said pulley can be clutched to the shaft. While any suitable clutch may be employed that which is herein shown is of the internal expanding type and it is actuated by a cone-shaped clutch actuator 18 which is slidably mounted on the shaft and which engages a clutch-actuating lever 19 which engages the cone-shaped portion of the clutch actuator 18 and by which the clutch is expanded into engagement with the driving pulley when the clutch actuator 100 is moved downwardly in Fig. 2. The movement of the clutch actuator 18 into the position shown in Fig. 2 allows the clutch to contract and thus to become disengaged from the driving pulley 16. The clutch actuator 18 is provided with a groove 27 in which is received a shoe 28 carried by the usual controlling lever 29 that is pivoted to the frame at 30.

The stitch-forming mechanism is driven from a driving shaft 20, as usual in sewing machines of this type, and said shaft is operated from a driving pulley 21 which is loosely mounted on the shaft and which is adapted to be clutched thereto by means of a friction clutch 39 of any suitable type, and which will be hereinafter referred to as the stitching clutch, that is controlled by the clutch actuator 22 which is slidably mounted on the shaft. This clutch actuator is given 110 its movement longitudinally of the shaft to clutch the pulley 21 to or unclutch it from the shaft by means of a clutch-actuating member in the form of an arm 23 having a roll 24 that operates in a groove 25 in the clutch actuator 22, which arm is fast on a rock-shaft 26 journaled in the frame. The rock-shaft 26 has depending therefrom an arm 32 carrying an adjustable stop screw 33, and this stop screw is adapted to engage the 125

end of a link 34 which is pivotally connected at one end to the controlling lever 29 and at its other end is pivotally connected to a positioning arm 35 that is pivoted to the frame 5 at 36. The arm 35 is for the purpose of holding the link 34 in proper position. The arm 32 is yieldingly held in engagement with the link 34 by means of a spring 37 which is connected at one end to the arm 32 10 and at the other end to the frame, and the controlling lever 29 is also acted upon by a spring 38 which tends to move it downwardly in Fig. 2.

With this arrangement, it will be seen 15 that when the clutch actuator 18 is moved upwardly, Fig. 2, to disengage the quick-feed clutch 17, such movement will operate through the link 34, arm 32, rock-shaft 26 and arm 23 to throw the stitching clutch 20 39 into operation. Similarly, a reverse movement of these parts will disengage the stitching clutch 39 and throw the quick-feed clutch 17 into operation.

In machines of this type means are provided for operating the feed cam 13 with a relatively-slow movement, while the stitching clutch 39 is in operation, so that the work will have the proper feeding movement during the stitching operation, and 25 this slow movement of the feed cam is usually derived from the driving shaft 20 for the stitch-operating mechanism. While any means might be employed for thus giving the feed cam its relatively-slow feeding 30 movement, I have herein shown a mechanism similar to that illustrated in my co-pending application Se. No. 100,124. The driving shaft 20 is provided with a worm or spiral gear 40 meshing with a gear 41 35 fast on a shaft 42, and this shaft carries at its lower end a bevel gear 43 which meshes with and drives a bevel gear 44 that is loose on the shaft 15. This gear 44 carries a pawl 45 which co-operates with a ratchet wheel 46 40 fast on the shaft 15. When, therefore, the quick-feed clutch 17 is thrown out of operation and the stitching clutch 39 is thrown into operation, the shaft 15 will be driven through the mechanism above described, 45 which is so constructed as to give the feed cam the desired relatively-slow feeding movement. In the construction herein illustrated, the worm 140 is mounted on the shaft 15 for longitudinal movement, but is held 50 from rotation thereon, and when the feed cam is being driven from the driving shaft 20 for the stitch-forming mechanism, the worm 140 is vibrated back and forth axially of the shaft 15 thereby to give an intermittent feeding movement to the feed cam. For this purpose, I have provided an elbow lever 47 pivoted at 48, and one arm of which 55 engages the gear 140, the other arm of which is connected by a link 49 with an eccentric 50 on the shaft 20. The worm 140

will thus be vibrated in timed relation with the operation of the stitch-forming mechanism. This device for giving the feed cam its relatively-slow feeding movement is fully illustrated and described in my above-men- 70 tioned co-pending application Se. No. 100,124.

In the operation of a sewing machine of this type, it is desirable that there should be no overlapping of operation between the 75 action of the quick-feed clutch 17 and of the stitching clutch 39. It will be observed that these clutches are so connected together that when the quick-feed clutch 17 is thrown out of operation or disengaged, the stitching 80 clutch 39 is thrown into operation or becomes engaged. As soon as the stitching clutch 39 becomes operative, the stitching mechanism will begin to operate and the needle 2 will make its first penetrating 85 thrust. At this time, the feed cam should be having its relatively-slow feeding movement. If, however, the quick-feed clutch 17 does not become fully disengaged before the stitching clutch 39 becomes operative, then 90 the feed cam will be operating at its relatively high rate of speed, and the work-holding means will consequently be moving with a rapid movement at the time that the needle makes its first penetrating thrust, 95 and if this occurs, the needle is apt to become broken.

One of the objects of my invention is to provide means which will obviate any possibility of any overlapping in the operation 100 between the disengagement of the quick-feed clutch 17 and the engagement of the stitching clutch 39.

The spring 38 tends normally to move the clutch actuator 18 downwardly in Fig. 2, 105 and thus hold the quick-feed clutch 17 in engagement, and at the same time, the spring 37 holds the stitching clutch out of engagement. I have provided herein spring-actuated means which become operative at 110 the proper point in the cycle of operations to give the link 34 a quick instantaneous movement upwardly in Fig. 2, thus to disengage the quick-feed clutch 17 and throw the stitching clutch 39 into operation, and this movement occurs with such rapidity 115 that there can be no overlapping of operations between these clutches. The link 34 has a pin or projection 50 extending therefrom which is adapted to be engaged by the 120 arm 51 of an elbow-lever pivoted to the frame at 52. The other arm 53 of this elbow-lever is acted upon by a strong pulling spring 54 which is also connected to the frame and which tends to swing the lever 125 into the full line position, Fig. 2, which is the position of the parts at the beginning of the stitching operation just after the quick-feed clutch 17 has been disengaged and the stitching clutch 39 has been en- 130

gaged. This elbow-lever is provided with an arm or finger 55 which coöperates with a cam 56 that is rigid with the feed cam 13, said cam 56 being shown as mounted adjustably on a hub 57 that depends from the feed cam 13. This cam 56 is provided with the concentric surface 58 and with the low portion or recess 59. So long as the cam is positioned so that the finger 55 engages the high concentric portion 58 of the cam, the elbow-lever will be maintained in the position shown in Fig. 7, and when said lever is in this position, the arm 51 thereof will permit a sufficient movement of the link 34 downwardly in Fig. 2 so as to cause the quick-feed clutch 17 to become engaged. When the machine is set in operation, the elbow-lever is held in the position shown in Fig. 7 by the cam 56, and the quick-feed clutch 17 will thus be operative to give the feed cam its quick movement. After the buttonhole has been cut and the work has been carried from buttonhole-cutting to stitching position, then the cam 56 has been turned sufficiently to allow the finger 55 to drop into the recess 59, and when this position is reached, the spring 54 which is a relatively strong spring will give the elbow-lever a quick movement into the position shown in Fig. 2 which will operate to disengage the quick-feed clutch 17 and to simultaneously throw the stitching clutch 39 into operation. Since this movement is almost instantaneous, there can be no objectionable overlapping of operations between the two clutches, and the feed cam will be entirely relieved from the operation of the quick-feed clutch before the needle makes its first penetrating thrust. As the feed cam continues its rotation during the stitching operation, the cam 56 operates on the finger 55 to move the elbow-lever into the position shown in Fig. 7, so that at the end of the stitching operation, the link 34 will be free to be moved toward the bottom of Fig. 2, thereby to disengage the stitching clutch 39 and to cause the quick-feed clutch to be engaged. The spring 54 which actuates the lever 53 is in the nature of a device tending normally both to disconnect the quick feed driving mechanism from the cam and to connect the slow feed driving mechanism thereto, and this normal tendency of the spring is restrained or overcome until the feed cam is in a predetermined position, at which time the spring is allowed to act to perform its function. The spring-actuated lever 53 might also be considered as a motor device or as a power device.

I have provided herein means similar to that illustrated in my co-pending application, Se. No. 100,124, for holding the stitching clutch 39 in engagement and the quick-feed clutch out of engagement during the stitching operation. The link 34 is pro-

vided with a nose 60 which is adapted to be engaged automatically by a catch 61 when the link 34 is moved into the position shown in Fig. 2, such catch 61 operating to hold the stitching clutch in operation and the quick-feed clutch disengaged. The catch 61 is shown as pivoted to the frame at 62. This catch is released at the end of the stitching operation thereby permitting the spring 38 to throw the quick-feed clutch 17 into operation again and disengage the stitching clutch 39. This release of the catch is accomplished by means associated with the stop mechanism by which the driving shaft 20 is brought to rest. This stop mechanism is similar to that shown in my co-pending application, Se. No. 113,445, filed August 7, 1916. The shaft 20 has fast thereon a brake drum 63 which is embraced by a brake member 64 fastened at one end to the rock shaft 65 and having connected to the other end thereof a link 66 which in turn is pivoted to a resiliently-sustained arm 67. 68 is a brake arm fast to the shaft 65 and having pivoted to the end thereof a strut member 69, the lower end of which rests on the end of the resilient arm 67. This strut member 69 has connected thereto a connection 70 provided at one end with a hook 71 and at the other end pivotally connected to a lever 72 that in turn is pivoted at 73 to the frame, said lever being acted upon by a spring 74 that normally tends to move the connection 70 to the right, Figs. 1 and 3. The hook 71 normally engages a keeper in the form of an arm 75 pivoted to the frame at 76, this arm having an extension 77 depending below its pivot point, which extension is acted upon by a spring 78 that normally holds the arm in position to be engaged by the hook 71. The extension 77 of the arm 75 carries an adjustable stop-screw 79 which is adapted to be engaged by the lever 80 by which the sector 8 is given its turning movement. This arm 80 derives its movement from the feed cam 13, as usual in sewing machines of this type, and the parts are so arranged that said arm will engage the stop-screw 79 at the time when the stitching on the buttonhole has been completed.

The shaft 65 also has fast thereto an arm 81 carrying at its end a pin or projection 82 that engages a track 83 formed on a head or thumb-piece 84 fast to the shaft 20. The rock shaft also has rigid thereon a rearwardly-extending arm 85 to which is connected a thrust member 86 that engages one end of the catch 61. So long as the hook 71 of the connection 70 engages the keeper 75, the brake arm 68 will be held out of engagement with the brake drum and the shaft 65 will be held in such position that the pin 82 will be out of engagement with the track 83 and the strut member 86 will permit the catch 61 to have its operative

position shown in Fig. 2. When in the cycle of operations the stitching on a buttonhole has been completed, the arm 80 will be brought into engagement with the stop-
 5 screw 79 and the keeper 75 will be turned about its pivot, thereby to disengage it from the hook 71. The spring 74 will tend to move the connection 70 backwardly and this will operate through the strut 69 to
 10 raise the brake arm 68 and thereby turn the shaft 65. This turning movement, however, is arrested by the projection 82 coming against the track 83, but as soon as the rotation of the shaft has brought the low
 15 portion 87 of the track into alinement with the projection 82, then the spring 74 will act to draw the connection 70 farther to the rear, thus applying the brake, and at the same time causing the shaft 65 to be rocked
 20 sufficiently so that the catch 61 will be disengaged from the nose 60 through the arm 85 and thrust pin 86, thus allowing the spring 38 to throw the quick-feed clutch 17 into engagement and disengage the stitch-
 25 ing clutch 39. The stitching clutch can thus be disengaged only when the shaft 20 is in a predetermined position and the stop mechanism so arranged as to bring the shaft to rest instantly that the clutch 39 is dis-
 30 engaged and always with the parts in a pre-
 determined position. The lever 72 is pro-
 vided with a pin or projection 88 situated to be engaged by the end of the slide 12, part of which is shown in dotted lines Fig.
 35 3. This slide thus operates at the proper time in the cycle of operations to restore the connection 70 into a position where the hook 71 may engage the keeper 75, thus placing the stop mechanism in position to
 40 be again operative at the end of the stitching operation.

I have herein illustrated a brake device to act on the shaft 15 at the time that the quick-feed clutch is disengaged, which
 45 brake device is for the purpose of assisting in arresting the momentum of the parts due to the high speed operation. This brake is shown as a brake drum 89 which is fast on the shaft and is acted upon by a brake shoe
 50 90 pivotally mounted on a lever 91 that in turn is pivoted at 92 to the frame. The end 93 of this lever is in position to be engaged by a cam projection 94 formed on the feed cam 13, and said projection is so
 55 situated that it will engage the lever 91, thereby applying the brake 90 just at the time that the elbow-lever 51, 53 is actuated to disengage the quick-feed clutch 17 and throw the stitching clutch 39 into engagement.
 60 The brake will thus assist in arresting the momentum of the parts due to the operation of the quick-feed clutch so that the change from high to low speed will occur without any jar.

65 95 is a spring acting on the lever 91 and

which may be adjusted to apply continuously to the brake drum 89 a slight braking pressure.

It will be remembered that at the end of the stitching operation the stitching clutch 39 is disengaged and the quick-feed clutch 17 is rendered operative thereby to give the feed cam a quick movement to carry the parts from stitching to buttonhole-cutting position. At the end of the cycle of operations it is necessary to disengage the quick-feed clutch 17 thus to bring the parts to rest. This is herein accomplished by a wedge member 96 which is adapted to be inserted between a projection 97 carried by 70 the controlling lever 29 and a pin or projection 98 that is carried by the starting lever (not shown), all as shown in my Patent No. 1,188,943. This wedge member 75 is pivotally connected to a lever 99 which in 80 turn is pivoted at 100 to the frame, and the end 101 of said lever is situated to be engaged by the end of the slide 12. 102 is a spring acting on the wedge member 96 and tending to hold it against the projection 97. 90 At the end of the cycle of operations the slide 12 engages the end 101 of the lever 99, thus advancing the wedge member 96 between the projections 97 and 98, and the action of the wedge against the projection 95 97 will move the lever 29 upwardly in Fig. 2 a sufficient distance to disengage the quick-feed clutch 17, and said clutch will remain thus disengaged until the machine is started again. When the machine is 100 again set in operation, the usual starting lever is actuated, thus removing the pin 98 from engagement with the wedge member, and allowing the spring 38 to come into play to throw the clutch 17 into engagement, 105 all as illustrated in the above-mentioned patent.

The controlling cam 56 is adjustably mounted on the hub 57 so that the change from the quick-feed to the slow-feed movement may be accomplished at any desired point in the cycle of operations.

103 indicates a lever pivoted to the frame at 104 and adapted to bear against the brake drum 63. This lever has an extension 105 110 that engages the portion 106 of the controlling lever 29. The brake drum is provided with a recess 107 situated in the plane of the arm 103. When the latch 61 is disengaged from the nose 60 of the link 34, the spring 38 will tend to move the lever 29 into position to cause the clutch 17 to be engaged, but this movement will be prevented by the lever 103 until in the rotation of the brake drum the recess 107 comes opposite the upper end of the lever 103. This lever 103 thus cooperates with the stop mechanism above described to insure that the operations of stopping the stitch-forming mechanism and shifting from the rela- 120 125 130

tively-slow feeding movement to the quick-feeding movement will be accomplished in proper timed relation.

While I have illustrated in the drawings 5 a selected embodiment of my invention, I do not wish to be limited to the constructional features shown.

I claim:

1. In a buttonhole-sewing machine, the 10 combination with stitch-forming mechanism and work-holding means movable relative to each other, of a feed cam for giving said parts such relative movement, a quick-feed driving mechanism for giving the 15 feed cam a relatively-quick movement, a slow-feed driving mechanism for giving the cam a feeding movement, a device tending at all times both to disconnect the quick-feed driving mechanism from the cam and to 20 connect the other driving mechanism thereto, and means to hold said device inoperative until the feed cam is in a predetermined position.

2. In a buttonhole-sewing machine, the 25 combination with stitch-forming mechanism and work-holding means movable relative to each other, of a feed cam for giving said parts such relative movement, a quick-feed driving mechanism for giving 30 the feed cam a relatively-quick movement, a slow-feed driving mechanism for giving the cam a feeding movement, a device tending normally both to disconnect the quick-feed driving mechanism from the cam and to 35 connect the other driving mechanism thereto, and means rigid with the feed cam for holding said device inoperative until the feed cam is in a predetermined position.

3. In a buttonhole sewing machine, the 40 combination with stitch-forming mechanism and work-holding means capable of relative movement to carry the parts from buttonhole-cutting to stitching position and then to give the parts a relative feeding 45 movement, of a feed cam for thus relatively moving said parts, a quick-feed driving device for moving the cam with a relatively-quick movement to carry the parts from buttonhole-cutting to stitching position, an- 50 other driving device for moving the cam with a relatively-slow feeding movement during the stitching operation, a device normally tending both to disconnect the quick-feed driving device from the feed cam and to 55 connect the other feeding device thereto, and means to hold said device inoperative until the feed cam is in a predetermined position.

4. In a buttonhole sewing machine, the 60 combination with stitch-forming mechanism and work-holding means capable of relative movement, of a feed cam for moving said parts relatively, two driving elements for operating the feed cam, one of

which gives the feed cam a relatively-quick 65 movement, and the other a relatively-slow movement, a spring to disconnect the quick-feed driving element from the cam and to connect the other driving element thereto, and means to hold the spring inoperative 70 until the feed cam is in a predetermined position.

5. In a buttonhole-sewing machine, the combination with stitch-forming mechanism 75 and work-holding means capable of relative movement, of a feed cam for moving said parts relatively, a quick-feed driving device for operating the cam, a slow-feed driving device also adapted to operate the cam, a spring to disconnect the quick-feed driving device from the cam and to connect the slow-feed driving device thereto, and means rigid with said feed cam to hold the spring inoperative until the feed 80 cam is in a predetermined position.

6. In a buttonhole sewing machine, the combination with stitch-forming mechanism, of work-holding means, a feed cam for moving said parts relative to each other, a quick-feed driving means for the cam including a quick-feed clutch, a slow-feed driving means for operating the feed cam including another clutch, connections between said clutches whereby when the quick-feed clutch is disconnected the other clutch is rendered operative, a spring-actuated member to operate said connections to disconnect the quick-feed clutch, and means to hold said member inoperative until the feed cam is in a predetermined position.

7. In a buttonhole sewing machine, the combination with stitch-forming mechanism, of a driving clutch therefor, work-holding means, a feed cam for moving the stitch-forming mechanism and work-holding means relatively, a quick-feed driving device for said feed cam, means for operating the cam from the driving clutch of the stitch-forming mechanism, spring-actuated means to disengage the quick-feed driving device and render the driving clutch of the stitch-forming mechanism operative, and means to hold said automatically-operative means inoperative until the feed cam is in a predetermined position.

8. In a buttonhole sewing machine, the combination with stitch-forming mechanism, of a driving clutch therefor, work-holding means, a feed cam for moving the stitch-forming mechanism and work-holding means relatively, a quick-feed driving device for said feed cam, means for operating the cam from the driving clutch of the stitch-forming mechanism, automatically-operative means to disengage the quick-feed driving device and render the driving clutch of the stitch-forming mechanism operative, means to hold said automatically-

operative means inoperative until the feed cam is in a predetermined position, and means to retard momentarily the movement of the feed cam when the quick-feed clutch is disconnected.

9. In a buttonhole sewing machine, the combination with stitch-forming mechanism and work-holding means capable of relative movement, of a feed cam for moving said parts relatively, a quick-feed driving device for operating the cam, a slow-feed driving device also adapted to operate the cam, a lever operatively connected to said driving devices, a spring to actuate said lever thereby to disconnect the quick-feed device from the cam and to connect the slow-feed driving device thereto, and means to hold said lever inoperative until the feed cam is in a predetermined position.

10. In a buttonhole sewing machine, the combination with stitch-forming mechanism and work-holding means capable of relative movement, of a feed cam for moving said parts relatively, a quick-feed driving device for operating the cam, a slow-feed driving device also adapted to operate the cam, a lever operatively connected to said driving devices, a spring to actuate said lever thereby to disconnect the quick-feed device from the cam and to connect the slow-feed driving device thereto, and a cam member rigid with the feed cam and acting on said lever to hold it inoperative until the feed cam is in a predetermined position.

11. In a buttonhole sewing machine, the combination with stitch-forming mechanism, of work-holding means, a feed cam for moving said parts relative to each other, a quick-feed driving device for operating the cam, a slow-feed driving device also adapted to operate said cam, connections between said driving devices whereby when one is connected to the cam, the other is disconnected therefrom, a lever operatively connected to said connections, a spring tending normally to actuate the lever to render the quick-feed driving device inoperative and the slow-feed driving device operative, and a cam member rigid with the feed cam and operating to

hold said lever inoperative until the feed cam is in a predetermined position.

12. In a buttonhole sewing machine, the combination with stitch-forming mechanism and work-holding means movable relative to each other, of a feed cam for giving said parts such relative movement, a quick-feed driving mechanism for giving the feed cam a relatively-quick movement, a slow-feed driving mechanism for giving the cam a feeding movement, means to disconnect the quick-feed driving mechanism from the cam and to connect the other driving mechanism thereto, said means being operative automatically independently of said cam, and means to hold said first-named means inoperative until the feed cam is in a predetermined position.

13. In a buttonhole sewing machine, the combination with stitch-forming mechanism and work-holding means movable relative to each other, of a feed cam for giving said parts such relative movement, a quick-feed driving mechanism for giving the feed cam a relatively-quick movement, a slow-feed driving mechanism for giving the cam a feeding movement, a device in the nature of a motor to disconnect the quick-feed driving mechanism from the cam and to connect the other driving mechanism thereto, and means to hold said motor device inoperative until the feed cam is in a predetermined position.

14. In a buttonhole sewing machine, the combination with stitch-forming mechanism and work-holding means movable relative to each other, of a feed cam for giving said parts such relative movement, a quick-feed driving mechanism for giving the feed cam a relatively-quick movement, a slow-feed driving mechanism for giving the cam a feeding movement, a self-contained power device to disconnect the quick-feed driving mechanism from the cam and to connect the other driving mechanism thereto, and means to hold said power device inoperative until the feed cam is in a predetermined position.

In testimony whereof, I have signed my name to this specification.

JOHN KIEWICZ.
